UNITED STATES PATENT OFFICE

RICCARDO GIRARDELLI, OF ROME, ITALY.

TRANSMITTER FOR DISTANT CONTROLLING APPARATUS FOR ORDNANCE.

1,410,912.

Specification of Letters Patent. Patented Mar. 28, 1922.

Application filed January 16, 1914. Serial No. 812,529.

(GRANTED UNDER THE PROVISIONS OF THE ACT OF MARCH 3, 1921, 41 STAT. L. 1313.)

To all whom it may concern:

Be it known that I, RICCARDO GIRARDELLI, a citizen of the Kingdom of Italy, residing at Rome, Italy, have invented certain new and useful Improvements in a Transmitter for Distant Controlling Apparatus for Ordnance, of which the following is a specification.

The subject matter of this invention is a sighting and transmitting instrument for laying a gun from a distance which is provided with an arrangement for automatically allowing for the difference in the positions of transmitter and gun.

The invention will be described with reference to the accompanying drawings, wherein is shown an apparatus which enables the direction to be imparted to the gun directly from an observing station remote from the gun platform by the adjustment of a sighting telescope upon the target by means of a mechanical triangle in such a manner that the difference of the positions of transmitter and gun is allowed for.

Fig. 1 is a plan view, partially in section, of the subject matter of the invention.

Fig. 2 is a vertical section on the irregular line 2—2 of Fig. 1, looking in the direction of the arrow α .

Fig. 3 is a vertical section on the line 3—3 of Fig. 1 looking from the left, and

Figure 4 is a diagram showing the position of the gun, observing station and target with the mechanical triangle superimposed.

The sighting telescope A is attached to a cam plate A¹, lying upon the frame B and having a recess a² running radially in the direction of the sighting line. In the recess a² works a block C, which is carried on and rotates on a pin c¹ on the frame B. This block C carries a spiral pinion D, which gears into a series of teeth a³ on the cam plate A¹ arranged on one of the longitudinal sides of the recess a². By rotating the spiral pinion D, the eccentricity of the cam plate A¹, (that is to say the distance of its central axis projected through the point 1 in Fig. 1, from the axis of the pin c¹ projected through the point 2,) can therefore be varied as may be desired. The amount of eccentricity to be imparted is determined by a scale a⁴ inscribed along the edge of the recess a², and a reading off mark c² inscribed on the block C.

The cam plate A¹ is surrounded by a cam ring E, which is provided with a projection e¹ which has a frame-like opening e². This opening e², the central longitudinal plane of which passes through the central axis of the cam plate A¹, is bounded on both its longitudinal sides by sliding surfaces e³, by which the projection e¹ is guided on a block F, pivotally mounted on a pin f¹ on the frame B. The point through which the axis of the pin f¹ is projected is denoted by 3 in Fig. 1.

On the cam ring E is mounted a worm G, which gears into a series of teeth a⁵ on the cam plate A¹. The worm shaft is provided on one end with a milled head g¹, and carries on its other end a spur wheel g², which gears into a spur wheel h² on the rotary switch shaft H¹ of the transmitter H, which is mounted on the cam ring E and serves for the electrical transmission from a distance, of the angular movement of the rotary switch shaft.

The transmitter H may be constructed in any desired known manner. For example it may be of the construction described in the specification of my copending application Serial No. 583,642, filed Sept. 24, 1910 which is the same as British Letters Patent No. 22714/10 and be connected by a three phase conductor J to the electro-motor which serves to drive the directing mechanism of the corresponding gun.

The frame B, the cam plate A¹ with the block C, and the cam ring E with the projection e¹, form a mechanical triangle 1, 2, 3 (see Fig. 1), to which any desired form can be given by the rotation of the worm G and an alteration of the eccentricity 1, 2 produced by rotating the spiral pinion D. With the instrument properly adjusted it will then be possible in the manner described to give the mechanical triangle 1, 2, 3 such a form that it is similar to the triangle 1', 2', 3' shown in Fig. 4, and determined by the gun platform 1', the observing station 2' and the target 3'. The eccentricity 1, 2 in this mechanical triangle then possesses a value which is inversely proportional to the distance 3', 2' of the target from the observing station and the scale a⁴ must consequently be so arranged and numbered, that each division thereof corresponds to a definite distance of the target 3' from the observing station 2'.

In order to make the mechanical triangle 1, 2, 3 when using the instrument (see Fig. 1) similar to the triangle 1', 2', 3' (see Fig. 4), it is therefore only necessary to adjust, by rotating the spiral pinion D, the eccentricity 2-1 to a valve such that 2-1:2-3::2'-1':2':3' and to rotate the worm G to bring the side 2-1 into coincidence with the line 2'-3' (see Fig. 4).

The frame B is so set up at the observing station 2' (see Fig. 4), that points 2 and 2' coincide and the side 2, 3 of the triangle falls in the direction of the line, observing station—gun (2', 1'). As the distance 1' and 2' between the gun and the observing station is constant in the large triangle and the side 2, 3 is constant in the mechanical triangle, it will be obvious, in order to preserve the similarity between the two triangles, when the position of the target is changed, that the side 1, 2 opposite the angle at 3 in the mechanical triangle will have to be changed as to its length, that is, it will have to be increased or decreased in exact proportion with, but inversely to the range. Supposing for instance, that the target has traveled towards the observing station 2, to the point 3^a along the line 3', 2', or in other words, that the range has decreased then the angle 1', 3', 2' has increased, and is now represented by 1', 3^a, 2'. If now the distance 2-1^a be made of such value that 2-1^a:2-3::2'-1':2-3^a and the line 2-1^a brought into coincidence by the operation of worm G, with line 2'-3^a, then the mechanical triangle 2-3-1^a will be similar to the triangle 2'-3^a-1' since the angles 1'-2-3 and 1'-2'-3^a are equal and 2-1^a:2-3::2':1':2-3^a. Since angles 3'-1'-2'=3-1-2 and 3^a-1'-2'=3-1^a-2, then (3'-1'-2')-(3^a-1'-2') = (3-1-2) - (3-1^a-2). Hence the angle through which the gun must move to train on the target is equal to the angle through which the circular cam has to be turned. To adjust the gun the spiral pinion D is first rotated until the mark c^2 is opposite that division on the scale a^4 which corresponds to the distance of the target (3') from the observing station (2'), and which may be determined by means of a range finder for example.

If now the sighting telescope A be adjusted upon the target by rotating the worm G, the angle 1, 2, 3 of the mechanical triangle 1, 2, 3 will be equal to the angle 1', 2', 3' in the triangle 1', 2', 3', and furthermore, as now both triangles are similar, the angle 3, 1, 2 will be equal to the angle 3', 1', 2'.

In other words the range is first set off on the scale a^4 by turning the spiral pinion D. This will bring the point 1 nearer to or further away from the fixed point 2. Thereupon the line 1-2 is directed against the target by turning the worm G. This will again alter the position of point 1 relative to

the other fixed point 3, and simultaneously change the direction of the gun.

Since the angles of rotation of the worm G and consequently also of the switch shaft H¹ of the transmitter H, positively connected thereto by the spur wheel garing $g^2 h^2$, are proportionally equal to the variations of the angle 3, 1, 2, it is obviously possible at once to so construct the device that the lateral angles of rotation of the gun, which are proportionally equal to the angles of rotation of the switch shaft H¹ of the transmitter, shall be always equal to the variations of the angle 3, 1, 2, under the supposition that the eccentric, that is, side 1-2 has already been set to correspond with the range.

If therefore the gun has been once so adjusted that its direction forms with the line, gun-observing station (1', 2') the same angle as the side 3, 1 of the triangle does with the side 1, 2 of the triangle, the equality of these two angles remains permanently retained for a single range.

Now since owing to the above mentioned adjustments of the spiral pinion D and of the worm G the angle 3, 1, 2 is equal to the angle 3', 1', 2', the angle which the direction of the gun forms with the line 1', 2', must also be equal to the angle 3', 1', 2', that is to say the gun is directed laterally upon the target. It is merely necessary therefore, after the apparatus has been adjusted by means of the spiral pinion D to the range, that is, the distance between the observing station and the target, to direct the sighting telescope A against the target by turning it by means of the worm and hand wheel G g' in order to impart to the gun a lateral direction allowing for the difference of the instrument and the gun, correctly.

I claim:

1. Sighting and transmitting instrument for laying a gun from a distance automatically, said gun being situated at a known and invariable distance from said instrument and determined to be directed upon a target situated at a known, but variable, distance from said instrument; said instrument having three mechanically connected points forming a triangle adjustable to any desirable form; two of said three points being fixed and confining a side of invariable length, and one of the other sides of said triangle having a length adjustable to the actual distance between the instrument and the target; and the angle lying opposite to said side of invariable length in said triangle being adjusted to correspond to another angle lying between two lines imagined to be drawn from the gun to the instrument and the target respectively, by adjusting the said adjustable side of the triangle to its proper correlative length and positioning in line with the said target; said instrument com-

- prising a frame, a sighting device, a transmitter for electrically transmitting angular movements, means for adjusting said triangle side and angle; and mechanical connection between said angle adjusting means on said sighting device and transmitter respectively.
2. Sighting and transmitting instrument for laying a gun from a distance automatically, comprising a frame; a sight carrier in the shape of a circular cam and provided with a radial slot; a journal in said frame provided with a head engaging said slot; means for displacing said carrier relatively to said head; a sleeve engaging the cam surface of said carrier; a radial arm on said
- sleeve having a guideway; a block engaging said guideway; a pinion on said block revolubly mounted in said frame, the axes of said pinion, said circular cam and said journal being parallel; a transmitter for electrically transmitting angular movements, and gearing for driving said transmitter and revolving said carrier relatively to said sleeve. 20
